UNITED STATES PATENT OFFICE.

BENITO J. DONADA, OF REFUGIO, TEXAS, ASSIGNOR OF ONE-THIRD TO JAMES R. DOUGHERTY, OF BEEVILLE, TEXAS, AND ONE-THIRD TO BENJAMIN SHELTON, OF REFUGIO, TEXAS.

PRIMING DEVICE.

1,367,025.

Specification of Letters Patent.

Patented Feb. 1, 1921.

Application filed May 16, 1919. Serial No. 297,586.

To all whom it may concern:

Be it known that I, BENITO J. DONADA, a citizen of the United States, residing at Refugio, in the county of Refugio and State of Texas, have invented new and useful Improvements in Priming Devices, of which the following is a specification.

This invention relates to improvements in priming devices for internal combustion motors and the principal object of the invention is to provide means for introducing a mixture of gasoline and air into the manifold whenever desired.

Another object of the invention is to provide means for regulating the amount of air admitted to the manifold and to place the air pipe adjacent the exhaust manifold so that the air will be heated by the products of combustion.

Still another object of the invention is to provide an improved mixing device for delivering the air and gasoline into the manifold.

The invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a diagrammatic view showing one application of my invention;

Fig. 2 is a like view showing another application of my invention;

Fig. 3 is a view partly in section of the mixing device;

Fig. 4 is a sectional view of the gasoline controlling means;

Fig. 5 is a sectional detail of the air controlling means.

In these views 1 indicates the inlet manifold of an internal combustion motor and 2 indicates the carburetor connected with the lower end thereof. 3 is the exhaust manifold while 5 indicates the gasoline vacuum tank. In carrying out my invention I bore a hole in the inlet manifold to receive the mixing device 6 which has that portion which lies within the manifold, of

tubular shape and provided with the perforations 7. The projecting portion of said device receives one end of the gasoline supply pipe 8 and said portion is provided with a projection 9 for receiving the air pipe 10, the ends of said pipes or tubes being suitably connected with said device to prevent leakage. The air pipe 10 is bent to contact with the exhaust manifold 3 so that said pipe will be heated by the products of combustion and said pipe passes through the dash 11 and has its upper end connected with a screw threaded bushing 12 carried by the dash. This bushing is provided with the slots 13 for admitting air to the interior of the bushing and the tube and these slots are controlled by a cap 14 which engages said bushing. This cap is provided with a hand-hold 15 so that the same can be manipulated to close more or less the slots. The gasoline pipe 8 is connected with a tubular member 16 which has its lower end connected with the vacuum tank 5 and its upper end passing through the dash 11. This upper end is screw-threaded and receives a cap 17. This cap carries a valve rod 18 extending through the tubular member and provided at its lower end with a valve 19. This valve is adapted to engage with a valve seat 20 formed in the tubular member between the connection of the pipe 8 and its lower end. Thus by manipulating the cap 17 the valve 19 may be adjusted relative to the seat 20 so as to control the gasoline flowing from the tank 5 into the tube 8.

It will thus be seen that the engine may be primed with a mixture of gasoline and air which will be thoroughly mixed by the mixing device as it is introduced into the manifold. Both the supply of gasoline and air are controllable from the dash.

Fig. 2 shows the device applied to an automobile in which the gasoline tank 21 is located under the front seat and a vacuum tank is not used. In this form the main gasoline line 22 is provided with a T 23 and the tubular member 16' has its lower end connected with this T and the pipe or tube 8' leads from the tubular member to the end of the mixing device as before described. In this case the cap 17' of the tubular member would project through the floor of the automobile. This form of in-

vention operates similarly to that just described.

I make that portion of the tube 10 which rests on the exhaust manifold flexible, as at 10' so that in hot weather this part of the device may be lifted off the manifold.

My device acts to reduce the amount of gasoline used as the explosive mixture may be made leaner by reason of the fact that 10 the air is heated before it is introduced in the manifold. Any amount of air may be introduced by manipulating the cap.

It is thought from the foregoing description that the advantages and novel features 15 of my invention will be readily apparent.

I desire it to be understood that I may make changes in the construction and in the combination and arrangement of the several

parts, provided that such changes fall within the scope of the appended claim. 20

What I claim is:—

A device of the class described comprising a mixing device having perforations therein and adapted to engage with the inlet manifold, a pipe connecting said device with the gasoline supply, a valve controlling said pipe, means for controlling the valve from a point adjacent the driver's seat, an air pipe connecting with said mixing device and having its upper end carried by the dash, a slotted bushing connected with said pipe and carried by the dash and a cap engaging said bushing for controlling the supply of air to the pipe. 30

In testimony whereof I affix my signature. 35

BENITO J. DONADA.
